(57) **CLAIM**

The ornamental design for a hand-held computer input and control device, as shown and described.

DESCRIPTION

FIG. 1 is a side elevation view of the hand-held computer input and control device;

FIG. 2 is a top plan view of the hand-held computer input and control device; and,

FIG. 3 is a bottom plan view of the hand-held computer input and control device.

The broken line showing is for illustrative purposes only and forms no part of the claimed design.
